(57) **CLAIM**

The ornamental design for a charger, as shown and described.

DESCRIPTION

FIG. 1 is a front-left-side-top perspective view of a charger according to an embodiment;

FIG. 2 is a rear-left-side-bottom perspective view of the embodiment;

FIG. 3 is a left-side view of the embodiment;

FIG. 4 is a right-side view of the embodiment;

FIG. 5 is a front view of the embodiment;

FIG. 6 is a rear view of the embodiment;

FIG. 7 is a top view of the embodiment, and,

FIG. 8 is a bottom view of the embodiment.

The broken lines shown in the drawings depict portions of the charger that form no part of the claimed design.

1 Claim, 8 Drawing Sheets
